UNITED STATES PATENT OFFICE

FRANK B. PARSONS, OF PLAINVILLE, CONNECTICUT

ANTISKID CHAIN

Application filed October 16, 1930. Serial No. 489,111.

My invention relates to the class of devices equipped for temporary attachment to traction wheels to prevent slipping, and more particularly to such devices as embody lengthwise members in the form of chains, and crosswise members secured at intervals to and connecting said lengthwise members and an object of my invention, among others, is the provision of means whereby cross members of standard construction may be provided with means for ready attachment to and detachment from the lengthwise members.

One form of an attaching means embodying my invention, and in the construction and use of which the objects herein set out, as well as others, may be attained, is illustrated in the accompanying drawing, in which—

Figure 1 is a view of the ends of a cross chain equipped with my improved holder.

Figure 2 is a side view of the same.

Figure 3 is a view looking at the opposite side of the chain from that shown in Figure 1.

Figure 4 is a detail view showing the manner of inserting my improved holder in place.

Figure 5 is a plan view of the same.

In the accompanying drawing the numeral 6 indicates one of the side members of an anti-skid chain of the usual construction to which the cross members 7 are secured. In a common form of cross-link the end members are provided with hooks 8 that are engaged with the links of the side members of the chain and are then bent down by a tool usually supplied for the purpose to hold them in place. In fact, this form of construction of the end members of a cross-link has come to be standard equipment.

It is the purpose of my present invention to make use of this standard form of equipment and to so construct my improved holder that it may be readily attached to the end members of the cross-link with little difficulty.

To this end I provide a snap holder preferably made of thin resilient metal and comprising a base and a spring tongue 9. The tongue is bent backwardly to overlie the base, and as shown in Figure 2 of the drawing. The base comprises a pad 10 at its front

end of a width to overlie the under portions of the hooks 8 to retain the holder in place. The base is bent downwardly at a point between the pad 10 and a tongue support 11 comprising the rear end of the base. Ears 12 are formed on opposite sides of the support 11 to underlie the branches 13 of the hooks, and the bend between the base and the tongue 9 is narrowed to permit the tongue to pass upwardly between the branches 13. The tongue is broadened to a width substantially that of the pad 10, thereby overlying the branches 13.

This structure when viewed from the end presents a groove at opposite edges of the holder, the upper sides of the grooves being constituted by the edges of the tongue 9 and the lower parts of the grooves being constituted by the pad 10 and ears 12. This enables the holder to be inserted by a movement lengthwise of the branches 13, which branches may be slightly spread apart as shown in Figure 5 to permit insertion of the holder and may then be closed toward each other into their normal positions and in which positions the holder will be securely retained in place. The base of the holder is preferably of such length that its front edge will underlie the side part of the link with which the hook is engaged, and as shown in Figure 2 of the drawing, while the rear end of the base, which also constitutes the rear end of the holder, this being the bend between the tongue and the base, will lie substantially against the link 14 of the cross chain to which the end member or hook 8 is attached.

It will be seen from this description, taken in connection with the accompanying drawing, that I have provided a snap holder which may be readily secured to the hook of the cross member of an anti-skid chain with the use of tools, as pliers, readily at hand. The holder is of such shape and form that when in place it will readily maintain its position without any shaping of the hooks to accomplish this purpose. The length of the tongue 9 is preferably such that when the tongue is bent downwardly it will pass the side part of a link with which the hooks

are to be engaged. In short, my improved holder converts a hook of standard construction into a snap hook.

In accordance with the provisions of the patent statutes I have described the principles of operation of my invention, together with the device which I now consider to represent the best embodiment thereof; but I desire to have it understood that the device shown is only illustrative, and that the invention may be carried out by other means and applied to uses other than those above set out.

I claim:

15 1. A snap holder for use with an attaching hook comprising spaced branches having backturned open hooks at one end, said holder comprising a base and a backturned spring tongue both having lateral extensions 20 oppositely disposed to form, when viewed lengthwise of the holder, grooves at opposite edges thereof to receive the branches of said attaching hook when the latter are closed to normal positions, said base being adapted 25 to project through the hook between said branches whereby the opposite ends of the base rest against the hook on opposite sides thereof.

30 2. A snap holder for use with an attaching hook comprising spaced branches having backturned open hooks at one end, said holder comprising a base including a broadened pad and extended ears said base being adapted to project through the hook between 35 said branches, whereby the opposite ends of the base rest against the hook on opposite sides thereof, and a spring tongue backturned to engage underneath the ends of the hooks when the holder is slipped into position 40 between the branches of an attaching hook.

3. A snap holder for use with an attaching hook comprising spaced branches having backturned open hooks at one end, said holder comprising a base including a broadened pad and extended ears said base being adapted to project through the hook between 45 said branches, whereby the opposite ends of the base rest against the hook on opposite sides thereof, and a spring tongue backturned to engage underneath the ends of the hooks to which the holder is secured, said tongue being broadened to engage the side members of the hook near the base of the tongue.

4. A snap holder for use with an attaching hook comprising spaced branches having backturned open hooks at one end, said holder comprising a base including a broadened pad and a tongue support, a back-turned spring tongue projecting from said support, the bend between said tongue and support being narrowed to provide notches to receive the branches of an attaching hook, said base being adapted to project through the hook

between said branches and having one end offset from the plane of the opposite end, whereby said opposite ends of the base rest against the hook on opposite sides thereof being of a length to engage the hooks and the link to which the hooks are attached to prevent substantial endwise movement of the holder.

5. A snap holder for use with an attaching hook comprising spaced branches having backturned open hooks at one end, said holder comprising a base having an offset portion whereby the base is adapted to project through a hook between said branches from one side to the other side thereof, clips 75 projecting laterally from the base to engage a hook, a bend in the end of the base adapted to be located between the side members of a hook, and a spring tongue extending from said bend and adapted to lie against 80 said side of the hook at the extreme end of the base.
